CARD COMPRESSOR

Hugh B. Johnson, Rochester, N. Y.

Application August 21, 1942, Serial No. 455,590

3 Claims. (Cl. 129—27)

(Granted under the act of March 3, 1883, as amended April 30, 1928; 370 O. G. 757)

The invention described herein, if patented, may be manufactured and used by or for the Government for governmental purposes, without the payment to me of any royalty thereon.

The present invention relates to card compressors, and more particularly to compressors of the card follower type, arranged to compress a stack of cards in a file cabinet by exerting pressure against one end of the stack.

It may be explained that in numerous types of modern office machinery rather large pasteboard cards, suitably punched, are used to record pertinent information and that, to insure perfect operation of the machinery, these cards should be maintained in perfectly flat, smooth condition at all times.

The cards may be kept in this condition by storing in file cabinets having suitable compressors, or wedging structures, to bear against the end of the stack of cards in the cabinet and prevent any possibility of warping. Such structures are well known and many suitable types of such devices are in use and have been heretofore available as products of manufacture. All satisfactory types known to the present inventor, however, have been manufactured largely of metal, or have at least required some metal plates, sheets, stampings or clamps in order to function properly and to perform their essential purpose in a satisfactory manner. Under present circumstances, however, metal structures are not available, or at least not desirable, in view of the wartime necessity of conserving strategic materials.

It is therefore, the principal object of the present invention to provide a card compressor of novel mechanical design, such that it is adapted to be manufactured almost entirely of wood, or of other similar non-critical material.

A further object of the invention is to provide a card compressor of wood or other non-critical material and of such design as to include relatively few parts, each of the parts being of simple configuration, well adapted to manufacture on conventional types of work-working machinery, and adapted to withstand a considerable degree of abuse without appreciable wear or damage.

Referring now more particularly to the drawing attached to and forming a part of the present specification,

Fig. 1 is a side elevational view of a card compressor constructed in accordance with the teachings of the present invention.

Fig. 2 is a rear elevational view thereof, showing the compressor structure associated with the bottom panel of a card cabinet, and

Fig. 3 is a detail sectional view taken substantially on the plane of the line 3—3 in Fig. 2.

The compressor structure includes, in general, a flat pressure plate adapted to extend substantially across the card compartment in a file drawer at the rear of a stack of cards in order to bear against the rear of the stack and force the cards into tightly compressed relationship. The pressure plate is preferably slidably mounted on a split file drawer bottom, and wedging mechanism is provided so that the pressure plate may be firmly forced into engagement with the stack of cards.

As illustrated in the drawing, the pressure plate 10 consists of a relatively long, narrow and flat wooden board extending substantially across the width of the file drawer and of a height slightly greater than the width of cards to be filed in the drawer. The plate 10 rests on side panels 11 and 12 of the bottom of the drawer, and is anchored against removal from the drawer by means of a retaining anchor 13 screwed to the lower edge of the plate 10 by the wood screws 14 and 15 and spaced apart from the lower edge of the pressure plate by a spacing strip 16. The spacing strip 16 is slightly thicker than the panels 11 and 12 of the file bottom so that the pressure plate retaining anchor and spacer will be free to slide longitudinally along the file drawer, unless clamped in position by a device to be hereinafter described.

It has been pointed out, however, that the prime object of the invention is to provide a device adapted to be wedged into pressure engagement with the stack of cards (such as the stack 17, illustrated in Fig. 3), and to this end a suitable foundation and wedging mechanism is provided immediately behind pressure plate 10.

The wedging structure includes a foundation block 21 of rectangular configuration extending transversely across the file drawer, immediately behind the pressure plate 10 and in a position immediately above the panels 11 and 12, so that the opposite ends of the foundation block 21 will rest on and be supported by these panels. The pressure plate 10 and the foundation block 21 are slidably united by means of wood screws 22, which extend through washers 23 and are secured in the foundation block 21, as indicated at 24. The screws 22 extend through vertical clearance slots 25 so that vertical movement between the pressure plate 10 and the foundation block 21 is permitted; but the washers 23 bear against the bottom surface of counterbores 26, so that the pressure plate and foundation block are perma-

nently united and cannot separate from each other.

The rear face of the pressure plate 10 is provided with a pair of triangular braces 27 fixedly secured to the plate in any conventional manner, as by means of the wood screws 28 and 29. A wedge 31 is positioned between the upper surface of the foundation block 21 and the lower surface of the braces 27. The wedge 31 has a tapered portion 32 at its forward end and includes a transverse grip rail 33 extending its entire length so that it may be easily manipulated by hand, either to force the tapered portion 32 into wedging engagement with the braces 27, or to facilitate moving the wedge rearwardly to release it from such engagement.

The wedge 31 is slidably connected to the foundation block 21 by means of the screws 35 and washers 36. The screws 35 are threaded into the foundation block 21 and the washers 36 engage shoulders of the T slots 38 formed in the rear portion of the wedge 31. The arrangement is such that the wedge 31 is free to move forwardly or rearwardly but will be limited in its movement, so that it will not disengage the braces completely and so that it will not become separated from the foundation block.

The operation of the device is as follows:

The operator will fill the file drawer with the desired number of cards positioned in the stack 17 and will then draw the pressure plate 10 into firm engagement with the rear end of the stack, applying a reasonable degree of pressure against the cards to accomplish the preliminary compression. As the block 10 reaches its pressure position, the operator will move the wedge 31 forwardly, thus exerting a wedging action between the foundation plate, or block 21, and the pressure plate 10, to force the upper end or edge of the pressure plate firmly into engagement with the top of the stack of cards. The wedging engagement between the foundation block 21, wedge 31, and braces 27 will react to exert a clamping force between the retaining anchor 13 and the lower surfaces of the file floor 11 and 12, and will thus lock the compressor structure against relative movement with respect to the file drawer.

To remove the pressure and permit removal of cards from the stack, it is only necessary to grip the transverse rail 33 and shift the wedge 31 rearwardly to disengage the cam surfaces and loosen the structure for sliding movement along the panels 11 and 12.

From the foregoing it will be apparent that by practicing the teachings of the present invention a novel and entirely satisfactory card follower may be constructed having compression characteristics, so that it will not only act as a card follower, but will exert a compressing action in response to the operation of its wedging mechanism. Further, the construction and arrangement of parts of the structure are such that it may be constructed entirely out of wood or similar non-critical materials and so that it will function properly, without requiring any type of metal stampings, latches, plates, or similar devices that are difficult to obtain or require special tools or machinery to manufacture in mass production.

Having thus described my invention, what I claim as new and desire to secure by Letters Patent is:

1. In a filing drawer having a pair of bottom panels, in combination, a pressure plate consisting of a single, flat rectangular board of uniform thickness; a retaining anchor connected to said pressure plate and engaging the lower surfaces of said bottom panels; a foundation block behind the aforementioned pressure plate and resting in contact with the upper surfaces of the bottom panels of the file drawer; a slideable connection between the said pressure plate and foundation block; a brace on the rear face of said pressure plate, and a transverse wedge extending across the rear of said pressure plate and including a tapered portion adapted to be wedged between the upper surface of the foundation block and the lower surface of said brace.

2. In a filing drawer having a pair of bottom panels, in combination, a pressure plate consisting of a single, flat rectangular board of uniform thickness; a retaining anchor connected to said pressure plate and engaging the lower surfaces of said bottom panels; a foundation block consisting of a single long, slender rectangular wooden block extending transversely of the file drawer immediately behind the aforementioned pressure plate and resting in contact with the upper surfaces of the bottom panels of the file drawer; a slideable connection between the said pressure plate and foundation block consisting of a screw and slot behind the operating face of the pressure plate, a plurality of braces on the rear face of said pressure plate, and a single transverse wedge extending across the rear of said pressure plate and including a tapered portion adapted to be wedged between the upper surface of the foundation block and the lower surface of said braces.

3. In a filing drawer having a pair of bottom panels, in combination, a pressure plate consisting of a single, flat rectangular board of uniform thickness; a retaining anchor consisting of a single wooden strip below and in alignment with said pressure plate and connected thereto, together with a spacing strip interposed between said retaining anchor and the aforementioned pressure plate to maintain said anchor and plate in spaced-apart relationship above and below the lower panel surfaces of the bottom of the file drawer; a foundation block consisting of a single long, slender, rectangular wooden block extending transversely of the file drawer immediately behind the aforementioned pressure plate and resting in contact with the upper surfaces of the bottom of the file drawer; a slideable connection between the said pressure plate and foundation block consisting of a screw and slot behind the operating face of the pressure plate; a plurality of braces on the rear face of said pressure plate, and a single transverse wedge extending across the rear of said pressure plate and including a tapered portion adapted to be wedged between the upper surface of the foundation block and the lower surface of said braces; said wedge including a slideable retaining connection with the foundation block.

HUGH B. JOHNSON.
